UNITED STATES PATENT OFFICE.

JAMES L. DROHEN AND JOHN M. HACKETT, OF DUNKIRK, NEW YORK.

DESIGN FOR A SEED-CASE.

SPECIFICATION forming part of Design No. 34,153, dated February 26, 1901.

Application filed November 3, 1900. Serial No. 35,430. Term of patent 14 years.

To all whom it may concern:

Be it known that we, JAMES L. DROHEN and JOHN M. HACKETT, citizens of the United States, residing at Dunkirk, in the county of Chautauqua and State of New York, have invented and produced a new and useful Design for a Seed-Case, of which the following is a specification.

The accompanying drawing is a front elevation of a seed-case, showing our new design.

As shown in the drawing, the leading or material features of our design consist of a stepped series of cylindrical platforms or shelves between which are located annular series of radial partitions, providing steps between the platforms or shelves and annular series of radial pockets, while above the upper platform or shelf is located an ornamental cylindrical stepped head formed with a hemispherical crown.

The reference-numeral 1 designates a stand-

ard supported by legs 2, and above said standard are arranged a plurality of cylindrical platforms or shelves 3, which are graduated in diameter from the bottom to the top, the uppermost platform or shelf being surmounted by an ornamental pyramid 4. The spaces between the shelves or platforms 3 are divided by vertically-disposed radial partitions 5, each series of which is surrounded by a wire-binder 6.

We claim—

The design for a seed-case herein shown and described.

In testimony whereof we affix our signatures in presence of two witnesses.

JAMES L. DROHEN.
JOHN M. HACKETT.
